COIN PURSE OR SIMILAR ARTICLE

John H. Blackwell, Los Angeles, Calif.

Application June 21, 1948, Serial No. 147,102

Term of patent 14 years

(Cl. D87—3)

To all whom it may concern:

Be it known that I, John H. Blackwell, a citizen of the United States of America, residing at Los Angeles, in the county of Los Angeles and State of California, have invented a new, original, and ornamental Design for a Coin Purse or Similar Article, of which the following is a specification, reference being had to the accompanying drawing, forming part thereof.

In the drawing:

Fig. 1 is a top plan view of a coin purse, showing my new design;

Fig. 2 is a side elevational view of the coin purse; and

Fig. 3 is an isometric view thereof in an open position showing the coin compartments.

I claim:

The ornamental design for a coin purse, or similar article, substantially as shown.

JOHN H. BLACKWELL.
